UNITED STATES PATENT OFFICE.

IAN D. PATTERSON, OF AKRON, OHIO, ASSIGNOR TO THE GOODYEAR TIRE & RUBBER COMPANY, OF AKRON, OHIO, A CORPORATION OF OHIO.

MACHINE FOR MAKING FIBROUS COMPOSITION.

Application filed September 16, 1922. Serial No. 588,645.

To all whom it may concern:

Be it known that I, IAN D. PATTERSON, a citizen of the United States, and resident of Akron, Ohio, have invented new and useful Improvements in Machines for Making Fibrous Composition, of which the following is a specification.

My invention relates to a machine for making fibrous composition, and it has particular relation to machines of the Fourdrinier type, commonly used in the manufacture of paper.

More specifically my invention relates to a novel means for gradually applying pressure upon a fibrous composition, in order to properly compress the same, and to remove undesirable liquids therefrom.

The object of my invention is to provide a novel means for compressing the composition without injuring the fibers thereof or disturbing their felted relation.

Heretofore, it has been customary, in the manufacture of fibrous composition, to compress the same by causing it to be carried, by means of a traveling belt, beneath a pressure roller member. This member compressed the composition, but on account of the sudden application of the pressure, the fibers were frequently crushed and broken, and in many instances the felted relation of the fibers was disturbed, thus materially reducing the strength thereof. For this reason, the Fourdrinier machine, as heretofore constructed, could not be employed for the manufacture of any thick material, such as cardboard, which is now made up of laminations of relatively thin material.

By my invention I have eliminated the aforementioned objection by a novel means for gradually applying any desired pressure to a fibrous composition of any desired thickness in such manner as to obviate the possibility of breaking or crushing the fibers, and to avoid disarrangement of the fibers from their natural felted arrangement.

In the accompanying drawing:

Fig. 1 is a cross-sectional view of a machine for making fibrous composition, constructed in accordance with my invention, portions thereof being omitted for the sake of clarity; and

Fig. 2 is a plan view of a pressure applying plate employed in the machine illustrated in Fig. 1.

In the machine, a traveling screen 3 passes over an idling pulley 4, through an inclined plane 5, over a pulley 6, through an upper horizontal plane 7, over a driving pulley 8, and finally through a lower horizontal plane 9, back to the idling pulley 4. The screen 3 moves in the direction indicated by arrows 3^a. While passing through the inclined plane 5, a quantity of fibers, suitably treated, is disposed thereon. The fibers, in suspension in a liquid, are introduced to the carrier 3 by being deposited in a chamber 10 of which that portion of the carrier 3, which is disposed in the inclined plane 5, constitutes a side wall. A suction box 11, which cooperates with the chamber 10, draws the liquid, in which the fibers are suspended, through the traveling screen, leaving the fibers deposited thereon. The resulting fibrous composition, indicated at 12, is carried by the screen 3 into the horizontal plane 7, 75 where it is engaged by an auxiliary moving screen 13, which is mounted on pulleys 14, and moves in the direction indicated by arrows 13^a. The auxiliary screen may be driven by its contact with the fibrous composition 12, or it may be driven from the driving pulley 8, or driven separately. If driven separately, it is necessary that it be driven at the same rate of speed as is the screen 3, in order that the felted arrangement of the fibers be not disturbed thereby.

The pressure applying mechanism consists of a flat plate 15, provided with an upwardly curved portion 16 at the front end thereof, and a similar curved portion 17 at the rear end thereof. The plate is supported from a horizontally disposed stationary member 18 by means of a series of upright threaded supports and adjusting members 19 to 22, inclusive. The position of the plate 15 is controlled by so rotating the threaded supports 19 to 22 as to raise and lower the plate with respect to the stationary supporting member 18. By this mechanism the several portions of the plate may be so adjusted as to very gradually increase the pressure on the fiber composition, as it moves along the horizontal plane 7.

If so desired, the material may be washed by means of liquid sprays 23 disposed intermediate the threaded supports. The excess liquid from the sprays 23, or any liquid which may be displaced thereby, is collected

by means of a suction box 24, disposed beneath the screen 3 and adjacent to the sprays 23 and the pressure member 15. The plate 15 is perforated so as to permit the liquid 5 from the sprays 23 to come into contact with the material 12. As the screen 13 is interposed between the plate 15 and the fibrous composition 12, the material cannot in any way be injured therefrom.

10 From the foregoing description it will be apparent that I have provided a simple and inexpensive method of applying an adjustable pressure upon the material 12 in order to compress the same. It will also be 15 apparent that this pressure exerting mechanism can in no wise injure the material, owing to the protection afforded by the belt 13. Also, it will be observed, that the tension of the traveling screens 9 and 13 is such 20 that the pressure exerted by the plate 15 is being applied very gradually, even before the material comes beneath the plate 15, and that the material is thoroughly protected against any sudden application of pressure, 25 which might tend to injure it.

Although I have illustrated but a single form of my invention and have described in detail but a single application thereof, it will be apparent to those skilled in the 30 art that it is not so limited, but that various minor changes and modifications may be made therein without departing from the spirit of my invention, and I desire to be limited only by the scope of the appended 35 claims.

What I claim is:

1. A machine for making fibrous composition comprising means for transporting the composition, and means for gradually 40 compressing the same, said last mentioned means comprising a perforated flat pressure plate.

2. A machine for making a fiber composition comprising a movable screen adapted 45 to transport the fiber composition, an auxiliary screen adapted to engage and move with the fiber composition deposited upon the transporting screen, and a flat perforated plate adapted to engage the auxiliary screen 50 for compressing the fiber composition.

3. A machine for making a fiber composition comprising a movable screen adapted 55 to transport the fiber composition, an auxiliary screen adapted to engage and move with the fiber composition deposited upon the transporting screen, and a flat perforated plate adapted to engage the auxiliary screen for compressing the fiber com-

position, said plate being adjustable with 60 respect to the screens.

4. A machine for making a fiber composition comprising a movable screen adapted to transport the fiber composition, an auxiliary screen adapted to engage and move with the fiber composition deposited upon the transporting screen, and a flat plate adapted to engage the auxiliary screen for compressing the fiber composition, and means for adjusting the several portions of said plate with 70 respect to said screens.

5. A machine for making a fiber composition comprising a movable screen adapted to transport the fiber composition, an auxiliary screen adapted to engage and move with the fiber composition deposited upon the transporting screen, and a flat plate adapted to engage the auxiliary screen for compressing the fiber composition, the leading edge of 75 said plate being so curved as to permit of easy introduction of the composition to the 80 plate.

6. A machine for making a fiber composition comprising a movable screen adapted to transport the fiber composition, an auxiliary screen adapted to engage and move with the fiber composition deposited upon the transporting screen, and a flat perforated plate adapted to engage the auxiliary screen for compressing the fiber composition, the leading portion of 85 said plate being adapted to exert a relatively light pressure on said fiber composition and the trailing portion of said plate to exert a relatively 90 heavy pressure thereon.

7. A machine for making a fiber composition comprising a movable screen adapted to transport the fiber composition, an auxiliary screen adapted to engage and move with the fiber composition deposited upon the transporting screen, and a flat perforated plate adapted to engage the auxiliary screen for compressing the fiber composition, the leading portion of said plate being adapted to exert a relatively light pressure on said fiber composition and the trailing portion of 100 said plate to exert a relatively heavy pressure thereon, and means for adjusting the pressure of the several portions of the 105 plate.

In witness whereof, I have hereunto 110 signed my name in the presence of two subscribing witnesses.

IAN D. PATTERSON.
